UNITED STATES PATENT OFFICE

166,022

GRAVY BOAT

Charles O. Bliss, Los Angeles, Calif.

Application November 14, 1951, Serial No. 17,412

Term of patent 14 years

(Cl. D44—10)

To all whom it may concern:

Be it known that I, Charles O. Bliss, a citizen of the United States, residing at 6674 Santa Monica Boulevard, Los Angeles, in the county of Los Angeles and State of California, have invented a new, original, and ornamental Design for a Gravy Boat, of which the following is a specification, reference being had to the accompanying drawing, forming a part thereof.

Fig. 1 is a side elevational view of a gravy boat embodying my new design;

Fig. 2 is a top plan view;

Fig. 3 is a bottom plan view; and

Figs. 4 and 5 are respectively front and rear elevational views thereof.

I claim:

The ornamental design for a gravy boat, as shown.

CHARLES O. BLISS.
